UNITED STATES PATENT OFFICE.

OSCAR L. OWEN, OF WHITINSVILLE, MASSACHUSETTS, ASSIGNOR TO THE WHITIN MACHINE WORKS, INCORPORATED, OF WHITINSVILLE, MASSACHUSETTS.

TAKE-UP MOTION FOR LOOMS.

SPECIFICATION forming part of Letters Patent No. 732,436, dated June 30, 1903.

Application filed November 14, 1901. Serial No. 82,236. (No model.)

To all whom it may concern:

Be it known that I, OSCAR L. OWEN, a citizen of the United States, residing at Whitinsville, in the county of Worcester and State of Massachusetts, have invented a new and useful Improvement in Take-Up Motions for Looms, of which the following is a specification.

In the weaving of cloth in a loom when the shuttle has failed to lay a weft-thread the weft-fork connects with the weft-hammer and causes the rock-shaft to be operated to disengage the shipper-lever, which now leads the belt from the tight pulley to the loose pulley and causes the loom to stop. During the interval of time between the movement of the rock-shaft and the stopping of the loom the mechanism of the loom continues to act. The take-up mechanism continues to take up cloth, although no filling may be supplied. Thin and imperfect cloth is therefore produced.

The object of my invention is to arrest the cloth take-up as soon as a fault is detected by the weft-fork; and to this end the invention consists in the peculiar and novel construction of the take-up mechanism more fully set forth hereinafter.

Figure 1 is an end view showing the parts of the mechanism of the loom required to illustrate the invention. Fig. 2 is a plan view of part of the top of the loom, shown partly in section. Fig. 3 is a side view, partly in section, of the latch-head by which the take-up mechanism is held in the disengaged position. Fig. 4 is a bottom view of the bracket on which the latch-head is supported.

In carrying out my invention I provide the end of the cam-shaft on the loom with a bevel-gear and with a bracket supporting a sleeve in which a shaft is rotatably supported. A bevel-gear on the shaft engages with the bevel-gear on the cam-shaft. On the so-driven shaft, which extends obliquely from the cam-shaft, a worm is secured which engages with the ratchet-gear through which the sand-roll is operated. The oblique shaft is supported near its upper end in a bracket secured to the rock-shaft, so that when the rock-shaft is partly rotated by the detector mechanism the oblique shaft is raised out of

engagement with the ratchet-gear and the take-up of the cloth is instantly arrested.

In the drawings, A indicates the end frame of the loom; B, the breast-beam; b, the weft-hammer; b', the weft-fork slide; b², an arm connecting the weft-slide with the rock-shaft b³, and b⁴ the usual spring-shipper. The cam-shaft a has secured to it the bevel-gear a', and journaled on it the bracket a², in the sleeve a³ of which is journaled the shaft a⁴, on the lower end of which is secured the bevel-gear a⁵, meshing with the bevel-gear a'. The shaft a⁴ extends obliquely from the cam-shaft a toward the rock-shaft b³ and has secured to it the worm a⁶, formed to engage with the ratchet-gear c, with which the pawl c' engages to hold the ratchet-gear in the advanced position. On the shaft of the ratchet-gear c is the pinion c², which engages with the gear of the sand-roll. (Not shown.)

To the end of the rock-shaft b³ is secured the bracket b⁴, the opposite end of which is pivotally secured to the collar b⁵, embracing the shaft a⁴, but loose on the same.

To the end frame A at the breast-beam B is secured the bracket d, the arm d' of which is provided with the elongated opening d². The edge d³ is undercut, so as to engage with the hook d⁴ of the latch-head d⁵, the stud d⁶ of which is provided with flattened sides and extends through the elongated opening d² in the arm d'. The shaft a⁴ extends through the latch-head d⁵ with a loose sliding fit. The collar d⁷ is secured to the end of the shaft a⁴.

To enable others skilled in the art to use my invention, I will now more fully describe its operation. When the parts are in the normally operative positions (shown in Fig. 1) and the loom is running, the worm a⁶ is in engagement with the ratchet-gear c, which controls the rotation of the sand-roll and the take-up of the cloth. The worm securely locks the ratchet-gear, so that it cannot be moved by hand, as is the case when the ratchet-gear c is operated by a reciprocating pawl mechanism in which the take-up mechanism may be and at times is operated by hand to secure a surreptitious gain of cloth. When now a shuttle fails to lay the required weft-thread, the weft-hammer operates the weft-slide to stop the loom in the usual manner

and also operates the rock-shaft b^3 . The bracket b^6 , rocking with the rock-shaft, raises the shaft a^4 and disengages the worm a^6 from the ratchet-gear c , which is, however, held in 5 the advanced position by the pawl c' . The hook d^4 of the latch-head engages with the edge d^3 and holds the shaft in the raised position with the worm a^6 disconnected from the take-up mechanism. By this arrangement 10 the take-up mechanism is disconnected at the same time with the release of the spring-shaft and the take-up of the cloth or the warp instantly arrested. The weaving of thin places in the cloth is avoided and the laborious 15 back winding of the warp and cloth unnecessary. On releasing the latch-head d^5 the worm engages with the ratchet-gear c and continues to take up the cloth as it is woven.

Having thus described my invention, I

claim as new and desire to secure by Letters 20 Patent—

In a loom, the combination with the ratchet-gear c , the shaft a^4 journaled in a bracket supported on the cam-shaft, the bracket a^3 , the cam-shaft, and the gears a^4 and a^5 , of the rock-shaft b^3 forming part of the detector mechanism, the bracket b^6 on the rock-shaft, the collar b^5 , the latch-head d^5 loose on the shaft a^4 , the bracket d , and the beveled portion d^3 on the bracket d , as described. 25

30 In testimony whereof I have signed my name to this specification in the presence of two subscribing witnesses.

OSCAR L. OWEN.
